UNITED STATES PATENT OFFICE.

JOHN WILLIAM GODDARD, OF LEICESTER, ENGLAND, ASSIGNOR TO UNITED SHOE MACHINERY CORPORATION, OF PATERSON, NEW JERSEY, A CORPORATION OF NEW JERSEY.

EYELETING MACHINE.

Application filed May 15, 1922, Serial No. 561,116. Renewed February 16, 1924.

To all whom it may concern:

Be it known that I, JOHN W. GODDARD, a subject of the King of England, residing at Leicester, Leicestershire, England, have invented certain Improvements in Eyeleting Machines, of which the following description, in connection with the accompanying drawings, is a specification, like reference characters on the drawings indicating like parts in the several figures.

This invention relates to machines for inserting fasteners and is herein disclosed as embodied in a machine adapted to perform blind eyeleting and invisible eyeleting as practiced in the manufacture of shoes. Inasmuch as a machine of the type herein illustrated is organized to insert the eyelets downwardly from above the work so as to utilize the lower tool to clench the barrels of the eyelets, it will produce blind eyeleting when the outer surface or upper leather is uppermost and invisible eyeleting when the reverse side or lining is uppermost. In each case the eyelet will be clenched between adjacent layers of the work, but when the upper leather is uppermost the flange of the eyelet will lie on that side and will therefore be visible on the exterior of the finished shoe, and when the reverse side is uppermost the flange of the eyelet will lie on that side and will therefore be on the inside of the finished shoe.

The present invention deals with blind or invisible eyeleting as performed by a setting tool formed and arranged to be passed through one or more layers of the work and having a clenching shoulder adapted to be positioned between adjacent layers of the work where it meets and spreads the entering end of the ingoing eyelet barrel clenching it between said adjacent layers. For invisible eyeleting the trade demands a small lacing-hole in the upper leather, preferably so small that it will be completely filled by the lacing, but in any event no larger than the internal diameter of the eyelet. This condition necessitates the passing of the clenching shoulder through a hole substantially smaller than the shoulder itself. Thus it is only by stretching the lacing-hole in the upper leather that the upper leather is forced past the clenching shoulder, the lacing-hole contracting after the withdrawal of the tool to somewhere near its original diameter.

The force required to pass the clenching shoulder through a layer of stock is comparatively small when the shoe upper is of leather that stretches easily, but when the upper is of tough leather that is difficult to stretch the thrust of the ingoing eyelet is often insufficient to force the upper leather past the clenching shoulder of the setting tool. When such layer, by failure to pass the clenching shoulder, remains in front of the shoulder while the eyelet is being inserted, the end of the eyelet barrel enters the upper leather, often passing through all the layers of the work before its leading end reaches the clenching shoulder, and the eyelet accordingly clenches imperfectly and frequently in such a manner that it is visible from the outside of the finished shoe instead of clenching between adjacent layers of the work.

In view of the foregoing, it is an object of the present invention to provide a machine for setting fasteners such as blind and invisible eyelets with mechanism arranged to force the outer layer of the work positively past the clenching shoulder of the setting tool so as to locate said shoulder in a predetermined position between adjacent layers of the work before the start of the clenching of the eyelet.

With this object in view, a feature of the invention comprises means, illustrated as an annular member, arranged to engage the work substantially at the edge of the lacing-hole while the lacing-hole is substantially at eyelet-inserting position and movable relatively to the fastener-inserting tool to force a layer of the material past the clenching shoulder of the tool. Thus the clenching shoulder is located in the desired position between adjacent layers of the work before the eyelet enters the work and therefore the eyelet is not relied upon to force the outer layer of the work past the clenching shoulder of the setting tool.

Another object of the invention is to provide an improved setting tool for blind and invisible eyeleting of such a nature that there will be comparatively little resistance to the movement of a layer of the work past the clenching shoulder of the tool.

The invention is illustrated as applied to an eyeleting machine of the type disclosed in United States Letters Patent 1,048,836 granted December 31, 1912, on an applica-

tion of A. E. Jerram. This patent discloses a machine equipped for ordinary visible eyeletting, but since the mechanism and operations for blind and invisible eyeletting do not differ essentially from those required for ordinary eyeletting excepting in the particulars hereinafter specified, the accompanying drawings are restricted to a comparatively simple disclosure which, when considered in conjunction with the complete organization disclosed in said patent, will be sufficient to enable one skilled in the art to practice the present invention.

With the above and other objects and features in view, the invention will now be described with reference to the accompanying drawings, and pointed out in the claims.

In the drawings, Fig. 1 represents an elevation partly in section of mechanism by which the article of work is forced upon the setting tool as hereinafter described;

Fig. 2 is a plan view of mechanism utilized to give the punch its work feeding movement;

Fig. 3 is a vertical section on an enlarged scale of a setting tool for clenching invisible eyelets, showing the outer layer of an article of work as having been forced past the clenching shoulder of the setting tool, said shoulder occupying the desired position between adjacent layers where the clenched portion of the eyelet is intended to lie;

Fig. 4 is a plan view of the member, shown also in Fig. 3, for forcing the outer layer of the work past the clenching shoulder of the setting tool;

Fig. 5 shows the two sets as having nearly completed the clenching of an eyelet, as a step subsequent to that shown by Fig. 3;

Fig. 6 is a side elevation of a fragment of the mechanism for pressing the layer through which the eyelet is not to pass past the clenching shoulder; and

Fig. 7 is a top plan view partly in section of the structure of Fig. 6.

Figs. 1 and 2 of the accompanying drawings will be recognized as corresponding in a general way to Figs. 2 and 4 of said Patent No. 1,048,836. Thus shaft 4 carries the several cams and other actuators by which the work-punching and setting tools, feeding mechanism and other movable elements are operated. The horn 89, which is fixed, supports a punch-block 88 on which the article of work lies while being punched, and fed by punch 6 and while being eyeleted. Punch 6 is carried upon one end of a bell crank lever 40, fulcrumed at 42 to a sleeve 43 mounted upon a shaft 45 journaled in the machine frame and having a toggle member 44 fulcrumed to its other extremity. Pivot-ed at 46 to toggle member 44 is a co-operat-ing toggle member 48 fulcrumed on a pin 50 provided with an adjustable eccentric bushing 52 rotatable by means of a hand

lever 54. Pivot 46 carries a roll 56 located in a cam track 58 formed in a cam carried by shaft 4. Thus, during the operation of the machine, punch 6 will be forced downwardly into contact with the punch-block 88 to perforate the work and later on in the cycle of operation of the machine will be withdrawn from the work. In order to cause punch 6 to feed the work, bell crank lever 40 is swung transversely by mechani-sm which will now be briefly described. A lever 60 (Fig. 2) fulcrumed at 61 to the machine frame carries a roll 62 operating in a cam track 63 in a cam carried by shaft 4. Lever 60 is adjustably connected as by a slide and block connection 64 to a link 65 pivoted at 66 to a guide member illustrated as provided with a pair of guide plates 67 straddling lever 40. Thus, as lever 60 is rocked about its fulcrum 61, it causes the punch to move back and forth, the forward or feeding movement of the punch taking place while the punch is in engagement with the work and the rearward or idle movement of the punch taking place after it has been withdrawn from the work. By adjusting the connection between lever 60 and link 65, the extent of the feeding movement of punch 6 may be varied. The foregoing mechanism is described in detail in said Patent No. 1,048,836, to which reference may be had for fuller description thereof.

The clenching tool is carried by a vertically movable carrier 90 and the presserfoot 100 is carried by a plunger 102 arranged to slide vertically in a fixture 104, and is normally drawn down by a tension spring 106. A link 108 connects the upper end of the plunger with a lever 110. The fulcrum of this lever is indicated at 112. A cam roll 114 carried by the lever is arranged to run on a cam 116 carried by the shaft 4.

The eyelets are inserted by a tool 51 (Fig. 5) carried by a plunger 52 as in said patent, this tool being provided with a spindle 72 arranged to pick an eyelet from the delivery end of a raceway (not shown) by which the eyelet is presented with its flange at the upper end of the barrel. The tool 51 does not move laterally.

The lower or setting tool remains in reg-istration with the inserting tool and is fixed relatively to its carrier 90 but guided by the punch-block 88. This setting tool is provided with a clenching shoulder 10 formed to pass through the lower layer or layers of the work. A pilot portion 11 pro-jects upwardly from said shoulder to guide the leading end of the eyelet barrel to the clenching shoulder. The body of the tool, behind the shoulder 10, is preferably pro-vided with a series of fine circular ribs or teeth 12 having sharp edges adapted to enter the lacing-hole in the lower layer of the work and maintain said hole in an ex-

panded condition. These teeth are preferably pitched away from the shoulder 10 so as to facilitate their entrance into the uneyeleted layer and to offer considerable resistance to withdrawal of the tool and upward movement of said layer. The specimen of work included in Figs. 3 and 5 represents a fragment of a three-ply shoe upper and includes an inside facing 13 such as leather, a lining 14 such as thin woven fabric, and an outer layer 15 of upper leather. In some cases the upper will include another layer such as an eyelet stay, usually made of a strong woven fabric that will not stretch. When an eyelet stay is used it is interposed between the other layers in such position as to form a bearing for the clenched portion of the eyelet.

As shown by Fig. 3 the article of work 20 has been pressed down relatively to the clenching tool far enough to force the layer 15 below the clenching shoulder and to locate the latter between the layers 14 and 15 so that the leading end of the eyelet bar- 25 rel will be transformed and clenched between said layers. A work positioning member 16, shown on an enlarged scale in Figs. 3 and 4, is provided with a hole 17 to receive the pilot portion 11 of the set- 30 ting tool, the annular work-engaging portion 18 of said member being formed and arranged to bear on the rim of the lacing-hole formed in the work. The member 16 is carried by a forked portion of an arm 35 19 to which it is connected by a pivot pin 20. A tension spring 21 is connected to the member 16 in such a way as to tend to raise the work-engaging portion 18, but a lug 22 formed on the member 16 is arranged 40 to engage the arm 19 so as to limit the relative angular movement of the members 18 and 19 in a clockwise direction as viewed in Fig. 1 and to permit relative angular movement in the opposite direction subject 45 to the tension of the spring. The arm 19 is anchored to a fixture 23 by a pivot pin 24 so that it may swing to carry the work- 50 engaging portion 18 up and down and also to move it to and from registration with the clenching tool as hereinafter described.

A link 25 forms operating connection between the arm 19 and a cam lever 26, the connection between the link and the lever being made by a simple pivot pin 27, and 55 the connection between the link and the arm 19 being made by an eccentric stud 28 and a spheroidal bushing 29. The purpose of the eccentric stud is to provide for adjusting the work-engaging portion 18 up and down relatively to the clenching tool according to the level of the clenching shoulder and also according to the thickness of the work to be eyeleted. The purpose of 60 the spheroidal bushing 29 is to avoid binding or cramping of the movable parts since,

in a machine organized as shown in said patent, it is convenient to arrange the axis of the anchoring pivot 24 otherwise than parallel to the axis about which the operating lever 26 swings. The lever 26 is arranged to 70 rock on the fulcrum 112 and carries a cam roll 30 which works in a cam groove 31 formed in the disk 118.

The form of the cam 31 is such as to 75 keep the link 25 raised excepting at that period in the cycle of operations between the completion of the work-feeding step and the step of inserting the eyelet, during which period the cam 31 acts to depress the link 25 and raise it to its initial position 80 without any dwell in the lower position. Fig. 1 shows these parts in their working position, the link 25 having been depressed to its lowest limit to depress the work to the position shown by Fig. 3. At this time 85 the member 16 and the arm 19 are, to all intents and purposes, a rigid unit since the lug 22 of the member 16 is bearing upon the arm 19 and the general direction of pressure is downward. However, when the arm 90 19 rises it first lifts the work-engaging portion 18 above the pilot portion 11, but the member 16 thereupon strikes a roll 32 and is deflected thereby so that it receives a component of motion about the axis of its 95 pin 20. This contact with the roll 32 so alters the movement of the member 16 that the work-engaging portion 18 moves substantially horizontally out of registration with the eyelet-engaging tools, the spring 21 100 yielding in response to the demands of relative angular movement between the members 16 and 19. The roll 32 is supported by a fixture 33 so that it remains always in one position to serve as an abutment to modify 105 the movements of the member 16 as just described.

In the course of a cycle of operations the punch 6 descends to the punch-block 88 to 110 punch a lacing-hole through all the layers of the work. The presserfoot 100 then rises to release the work so that it may be fed. The punch 6 then moves from right to left to feed the work so as to place the punched hole in registration with the eyelet-engaging 115 tools, the inserting tool at this time being in its upper position and the clenching tool being in its lower position. When the work has been fed as stated the presserfoot de- 120 scends to clamp it on the block 88 and then the punch 6 rises to clear the work and re- 125 turns to its initial position preparatory to punching the next hole. While the punch 6 is rising and moving from left to right the clenching tool, which up to this time has been depressed so far as to keep its pilot 11 below the top of the block 88, rises to the position shown by Figs. 3 and 5, and at the same time the cam 31 causes 130 the work-positioning member 16 to move 135

- first into registration with the eyeleting tools and then to press the work down until the bottom layer 15 is below the clenching shoulder 10. Having thus positioned the work 5 and the clenching tool in the desired operative relation the clenching tool remains stationary until the eyelet has been clenched, but the member 16 immediately rises far enough to clear the pilot 11 and then swings 10 out of registration with the eyeleting tools by reason of its engagement with the roll 32. The inserting tool 51, having by this time passed its spindle through the eyelet in the delivery end of the raceway (not 15 shown) continues to move downwardly with said eyelet which, instead of having to force one layer of the work past the clenching shoulder as heretofore, finds the work and the clenching tool in the relation shown by 20 Fig. 3 and has merely to pass through the hole in the layers 13 and 14 before reaching the clenching shoulder. The clenching operation thereupon takes place between the layers 14 and 15 and the inserting tool rises immediately to its initial position the clenching tool being timed to descend while the inserting tool rises. The various instrumentalities are then ready to begin another cycle 25 of operations.
- 30 The foregoing cycle of operations and the illustrated article of work have been described in terms of invisible eyeleting but it will be obvious that for purposes of blind eyeleting the work will be placed so that the outside layer or upper leather will be at the top instead of at the bottom and that the inside facing will then be the layer that will be forced past the clenching shoulder, and the barrel of the eyelet will then 35 pass through the outside layer and the lining (also the eyelet stay if the upper includes one) and will be clenched between the inside facing and the lining (or eyelet stay).
- Having thus described my invention, what 40 I claim as new and desire to secure by Letters Patent of the United States is:
1. An eyeleting machine comprising an eyelet-inserting tool and a clenching tool arranged in permanent coaxial relation to each other, said clenching tool having a clenching shoulder formed to pass through a lacing-hole in one layer of an article of work so as to clamp an eyelet between two layers of said article, and work-positioning 45 mechanism arranged to force the work onto said clenching tool far enough to place said shoulder between two of the layers before the eyelet is inserted.
  2. An eyeleting machine comprising an eyelet-inserting tool, a clenching tool fixed against lateral movement but movable longitudinally, said clenching tool having a clenching shoulder formed to pass through a lacing-hole in one layer of an article of work so as to clamp an eyelet between two 50

layers of said article, and work-positioning mechanism arranged to force the work onto said clenching tool far enough to place said shoulder between two of said layers before the eyelet is inserted.

70 3. An eyeleting machine comprising a tool arranged to carry an eyelet downwardly to insert it into an article of work, a clenching tool having a clenching shoulder formed and arranged to enter the work from beneath and to pass through the lacing-hole in the bottom layer of an article of work so as to clamp the eyelet between two layers of said article, and work-positioning mechanism arranged to force the work downwardly onto said clenching tool far enough to place said shoulder between two of said layers before the eyelet is inserted.

75 4. An eyeleting machine comprising a stationary work-support, a clenching tool arranged initially below the upper surface of said work-support but movable upwardly to operative position and having a clenching shoulder formed to pass through the lacing-hole in one layer of an article of work so as to clamp an eyelet between two layers of said article, work-positioning mechanism arranged to force the work downwardly far enough to place said shoulder between two of said layers, and a tool arranged to insert an eyelet downwardly into the work after the latter has been positioned relatively to said shoulder as aforesaid.

80 5. An eyeleting machine comprising a stationary punch-block, a punch movable downwardly against said punch-block to punch a lacing hole through an article of work lying on the block and movable laterally to feed the work while the punch is in the work, a clenching tool arranged initially below the upper surface of said block but movable upwardly to operative position after the work has been fed as aforesaid and having a clenching shoulder movable to a level above the punch-block and formed to pass through a lacing-hole in one layer of the article of work so as to clamp an eyelet between two layers, work-positioning mechanism arranged to force the work downwardly onto said tool so as to place said shoulder between said two layers, and a tool arranged to insert an eyelet downwardly into the work after the latter has been positioned relatively to the clenching shoulder as aforesaid.

85 100 105 110 115 120 125 130 6. An eyeleting machine comprising an eyelet-inserting tool, a clenching tool having a shoulder formed to pass through the lacing-hole in one layer of an article of work so as to clamp an eyelet between two layers of said article, a work-positioning member having an annular work-engaging portion, and mechanism arranged to impart a compound movement to said member such that one portion thereof carries said annular portion into registration with the clenching

tool and the other component causes the annular portion to force the work onto the clenching tool far enough to place said shoulder between said two layers before the eyelet is inserted into the work.

7. An eyeleting machine comprising an eyelet-inserting tool, a clenching tool having a shoulder formed to pass through the lacing-hole in one layer of an article of work so as to clench an eyelet between two layers of said article, a work-positioning member having an annular work-engaging portion, a reciprocatory carrier to which said member is pivotally connected and by which it is carried so as to force the work onto said clenching tool far enough to place said shoulder between said two layers, and means arranged to cause angular movement of said member relatively to said carrier to shift said annular portion to and from registration with the clenching tool.

8. A machine for inserting barreled fasteners having a setting tool provided with a clenching shoulder formed and arranged to be introduced from one side of the work through a hole in one of several layers of material to clench the barrel of a fastener between adjacent layers of the material, and means arranged to engage the material on the other side at the edge of and substantially surrounding the hole operative to force a layer of the material past the clenching shoulder of the tool.

9. A machine for inserting barreled fasteners having a setting tool provided with a pilot portion and provided also with a clenching shoulder formed and arranged to be introduced from one side of the work through a hole in one of several layers of material to clench the barrel of a fastener between adjacent layers of the material, and means arranged to engage the material on the other side at the edge of and substantially surrounding the hole after the pilot portion of the tool has been introduced and operative to force a layer of the material past the clenching shoulder of the tool.

10. A machine for inserting barreled fasteners having a setting tool provided with a clenching shoulder formed and arranged to be introduced from one side of the work through a hole in one of several layers of material to clench the barrel of a fastener between adjacent layers of the material, means acting in opposition to said tool arranged to engage the material on the other side at the edge of and substantially surrounding the hole, and mechanism for moving said means toward the clenching shoulder of the setting tool thereby forcing a layer of the material past the clenching shoulder of the tool.

11. A machine for inserting blind or invisible eyelets having a setting tool pro-

vided with a clenching shoulder formed and arranged to be introduced from one side of the work through a lacing-hole in one of several layers of material to clench the barrel of an eyelet between adjacent layers of the material; an annular member having an opening of substantially the same diameter as said clenching shoulder arranged to engage the material on the other side, and means for causing relative movement of the annular member and the clenching shoulder to force a layer of the material past the setting shoulder of the tool.

12. A machine for inserting blind or invisible eyelets having a setting tool provided with a clenching shoulder formed and arranged to be introduced from one side of the work through a lacing-hole in one of several layers of material to clench the barrel of an eyelet between adjacent layers of the material; means arranged to engage the material on the other side substantially at the edge of the lacing-hole while the lacing-hole is substantially at eyelet-inserting position, and mechanism for causing relative movement of the clenching shoulder and said means to force a layer of the material past the clenching shoulder of the tool.

13. A machine for inserting barreled fasteners in a plurality of layers of material and clenching the ends of the fastener barrels between adjacent layers of the material having, in combination, a punch-block, a punch movable against said punch-block to punch a lacing-hole through the material, said punch being movable transversely to feed the material to fastener-inserting position and then being withdrawn from the material, and a fastener-setting tool having a clenching shoulder formed and arranged to be introduced from one side of the material through a lacing-hole in one of the layers of the material to clench the barrel of a fastener between adjacent layers of the material.

14. A machine for inserting barreled fasteners in a plurality of layers of material and clenching the ends of the fastener barrels between adjacent layers of the material having, in combination, a punch-block, a punch, mechanism for moving said punch toward said punch-block to punch a hole through the material, for moving said punch transversely to feed the material to fastener-inserting position and for then withdrawing the punch from the material, and a fastener-setting tool formed and arranged to be introduced from one side of the material through a lacing-hole in one or more layers of the material and having a clenching shoulder adapted to be positioned between adjacent layers of the material to clench the barrel of a fastener between said adjacent layers.

15. Fastener-inserting mechanism com-

- prising a fastener-inserting tool, and a clenching tool having a clenching shoulder formed to pass through a hole in one layer of an article of work so as to clench a fastener between two layers of said article, said clenching tool having a plurality of fine encircling ribs behind said shoulder to engage and hold the wall of the hole in the layer first mentioned.
- 10 16. A clenching tool for blind and invisible eyeleting having a clenching shoulder formed to pass through the lacing-hole in one layer of an article of work so as to clench an eyelet between two layers of said article, and having a plurality of fine teeth behind said shoulder to enter said lacing-hole and maintain the latter in an expanded condition.
- 15 17. A clenching tool for blind and invisible eyeleting having a clenching shoulder formed to pass through the lacing-hole in one layer of an article of work so as to clench an eyelet between two layers of said article, and having a plurality of sharp edges behind said shoulder to enter said
- 5 lacing-hole and maintain the latter in an expanded condition.
18. A clenching tool for blind and invisible eyeleting having a clenching shoulder formed to pass through the lacing-hole 30 in one layer of an article of work so as to clench an eyelet between two layers of said article, and having a plurality of sharp-edged ribs behind said shoulder and pitched away from the latter to enter said lacing-hole and maintain the latter in an expanded condition.
- 35 19. A clenching tool for blind and invisible eyeleting having a clenching shoulder formed to pass through the lacing-hole 40 in one layer of an article of work so as to clench an eyelet between two layers of said article, and having a series of sharp-edged, ratchet-shaped, annular ribs behind said shoulder and pitched away from the latter 45 to enter said lacing-hole and maintain the latter in an expanded condition.

In testimony whereof I have signed my name to this specification.

JOHN WILLIAM GODDARD.
